ATTORNEY

UNITED STATES PATENT OFFICE

161,736

WALL MAGAZINE RACK

Harold D. Coddington, Park Forest, Ill., assignor
to Steger Furniture Manufacturing Company,
Steger, Ill.

Application August 11, 1950, Serial No. 11,727

Term of patent 3½ years

(Cl. D33—2)

To all whom it may concern:

Be it known that I, Harold D. Coddington, a citizen of the United States of America, residing at Park Forest, State of Illinois, have invented a new, original, and ornamental Design for Wall Magazine Rack, of which the following is a specification, reference being had to the accompanying drawing, forming part thereof.

In the drawing:

Fig. I is a front view of a wall magazine rack, showing my new design, and

Fig. II is a vertical cross-sectional view taken on a line located at the center of Fig. I.

I claim:

The ornamental design for a wall magazine rack, substantially as shown.

HAROLD D. CODDINGTON.
